UNITED STATES PATENT OFFICE

ARTEMAS S. HICKEY, OF LOS ANGELES, CALIFORNIA

SMOKER'S PIPE STEM UNIT

Application filed February 9, 1931. Serial No. 514,542.

This invention relates to smokers' pipes and more especially to the stem structures. It is an object of the present invention to provide a stem unit of such construction and arrangement of parts as to serve as a cooler for the smoke stream passing from the hot bowl to the mouth piece. A further object is to provide a smoke cooling stem which divides the stream into a number of short straight passageways which may be quickly and effectively cleaned from time to time and in this connection an object is to provide for the reduction of the smoke stream to a stream of relatively small cross section area to facilitate the transfer of its heat, and in this connection an object is to provide an aggregate length of reduced area of a smoke stream which will be sufficient to provide for the cooling of the smoke to the desired degree. For the accomplishment of this result and to obtain a sanitary stem unit the cooling means consists of a plurality of tubular conduits whose ends are set in headers one of which is adjacent to the bowl passage while the other 25 is adjacent to the mouth piece of the stem.

The invention consists in certain advancements in this art as set forth in the ensuing disclosure and having, with the above, additional objects and advantages, and whose construction, combination and details of means, and the manner of operation will be made manifest in the description of the herewith illustrative embodiment; it being understood that modifications, variations and adaptations may be resorted to within the scope, principle and spirit of the invention as it is more directly claimed hereinafter.

Fig. 1 is a side elevation of a pipe incorporating the cooling unit.

40 Figure 2 is an axial section of the cooling unit and a relative saliva screen.

Figure 3 is an end view of the cooling unit.

Figure 4 is a sectional view showing the method of crimping in a tubing header.

45 The cooling unit includes an exterior tubular shell 2 of suitable diameter and length and the lower end of it is attached in any suitable manner to the bottom of the pipe bowl 3. The upper end of the shell tube is attached 50 in any suitable manner to the mouth piece 4

and the shell 2 is provided with suitable perforations 5 for the free passage of air to and from its interior.

Set somewhat inwardly from each end of the jacket 2 are headers 6 so that there is 55 formed an upper of saliva screen chamber 7 for a suitable absorbent screen 8 and at the lower end is formed the smoke drawing chamber 9. Extending from header to header and hermetically sealed therein is a system of small tubular conduits 10 whose lower ends open into the bottom chamber 9 and whose upper ends open into the screen chamber 8. The conduits 10 are sufficiently spaced to provide for ready flow of air into and 60 from and throughout the space between the headers 6; this circulation being very active when the pipe is being used and when, because of suction in the chamber 7 at the mouth piece, the hot smoke, pressed by atmospheric pressure to the chamber 9, is divided into a number of small streams passing 65 into the spaced conduits 10. Because of such division of the smoke volume from chamber 9 into the conduits 10 the heat is rapidly dissipated at the initial ends of the conduits and by the time the smoke is at the suction chamber 7 the smoke has been reduced 70 to such temperature that it will not bite or sting the tongue.

75 While the cooling effect is the same as if the smoke passed through one long continuous passageway equaling the aggregate length of the conduits 10 the present device has the greater advantage because the system of conduits forms a short unit of plurality of straight passageways which can be quickly and thoroughly cleaned when needed, after removing the unit from the mouthpiece and bowl.

80 When the packing screen 8 is in place it serves to prevent the saliva from passing down into the stem parts.

An effective method of fixing the headers 6 in the shell 2 is shown in Figure 4. The header is about equal to the internal diameter of the shell and when these parts are assembled to the desired position then a crimping roller 11 may be employed to roll a clinching bead 12 about the header 6 so as to effectively 85 90 95 100

hold the header and make a leak-proof contact thereabout so that no smoke will pass into the air chamber between the headers.

As there is much moisture from even so called "dry" smoking tobacco this condensed liquid drains from the cooling unit to a capacious pocket in the bottom of the bowl, which is provided with a readily removable pack of absorbent material which catches the condensed moisture. Such a pack is clearly shown in my application No. 483,614.

What is claimed is:

1. A stem unit for a smoker's pipe, consisting of a shell with ends to which are attachable a mouth piece and a bowl, a set of sealable headers in the shell and spaced inwardly from its ends to form chambers for absorbent pads, and a system of straight, parallel, spaced conduits whose ends are sealed in the headers and open into the said end chambers; said shell being perforated for free flow of air to the space between the system of conduits to carry off heat from the smoke.
2. A device as set forth in claim 1, and in which one end of the shell has a conical plug part to fit a pipe bowl stem socket, and the other end has a conical end seal for the stem mouth piece.
